UNITED STATES PATENT OFFICE.

WARD RAYMOND, OF EASTON, PENNSYLVANIA, ASSIGNOR TO INGERSOLL-RAND COMPANY, OF JERSEY CITY, NEW JERSEY, A CORPORATION OF NEW JERSEY.

GOVERNING MECHANISM FOR STEAM-ENGINES.

1,177,895.

Specification of Letters Patent.

Patented Apr. 4, 1916.

Application filed July 13, 1914. Serial No. 850,547.

To all whom it may concern:

Be it known that I, WARD RAYMOND, a citizen of the United States, residing at Easton, in the county of Northampton and State of Pennsylvania, have invented a certain new and useful Improvement in Governing Mechanism for Steam-Engines, of which the following is a specification.

This invention relates to governing mechanism for steam engines, and more particularly to governing mechanism for steam engines of the puppet valve type.

Under ordinary operating conditions the governing of steam engines is effected by fly ball governors or similar devices which open or shut the valves according to the load, there being comparatively little variation in the speed of the engine. Under some conditions, however, such, for instance as encountered in driving compressors and pumps, the speed of the driving engine must vary through a wide range. Under such conditions governors of the fly ball type are not satisfactory, although various methods of modifying the action of the fly ball governor by means of the compressor discharge line pressure have been used with some success in connection with steam valves of the Corliss and Meyer types.

The object of the present invention is to provide a governing mechanism particularly adapted for use with steam engine valves of the puppet type which will enable the engine to be successfully operated through a wide range of speeds. With this object in view, a regulating mechanism has been devised, a practical embodiment of which is shown in the accompanying drawings, in which,

Figure 1 shows a plan view of a steam cylinder provided with a governing mechanism designed to be controlled by the speed and discharge line pressure of an air compressor, Fig. 2 shows a longitudinal section on a larger scale through the eccentric shaft, Fig. 3 a side elevation partly in section of the end of the eccentric shaft and the governor proper, Fig. 4 a transverse section through the governor on the line 5—5 of Fig. 2, and Fig. 5 a detail view showing the connection of the follow up lever of the governor pilot valve.

In the drawings is shown a steam cylinder 1, provided with inlet valves 2 and exhaust valves of the puppet type, not shown

herein, but such as shown, for instance, in the patent to Lentz, #659,892 dated October 16, 1900. Mounted parallel to the axis of the cylinder is an eccentric shaft 4 which is rotated through a rod 5 by a connection, not shown, from the main shaft of the engine. Mounted on the shaft 4 are two pairs of eccentrics, discharge valve controlling eccentrics 6 which are fixedly mounted eccentrically to the shaft, and inlet controlling eccentrics 7 which are adapted to slide inwardly and outwardly on eccentrically arranged squared portions 8 of the shaft to vary the throw of the valve and hence the amount of intake. Projecting from the inner faces of the eccentrics 7 are lugs 9 to which are pivoted short links 10 which are, in turn, pivotally secured to arms 11 of bell crank levers 12. The bell crank levers 12 are fulcrumed on pins 13 secured in lugs 14 projecting from the shaft 4. Slidably mounted in the interior of the shaft is an operating rod 15, for actuating the bell crank levers 12, the rod 15 having toothed portions 16 engaging toothed sections 17 on the inner arms of the bell crank levers 12.

The rod 15 is extended axially of the shaft 4 into a stationary motor casing 18 which abuts against the end bearing 19 of the shaft. At the extreme end of the rod 15 is a collar or flange 20 which rotates in a coupling nut 21 which is attached to a longitudinal operating stem 22. The stem 22 is moved inwardly by means of a piston 23 sliding in a cylinder 24 and is moved outwardly by a spring 25 pressing against a head 26 secured to the stem 22. Oil is admitted and exhausted from the cylinder 24 to move the piston 23, through a pipe 27 which leads to the governor proper.

Considering the operation of the parts which have been described: When oil is admitted to the cylinder 24 the piston 23 will be moved inwardly moving the stem 22 and the coupling nut 21 against the resistance of the spring 25. The movement of the coupling nut 21 will cause a corresponding longitudinal movement of the rod 15 without affecting its rotation in any way. This longitudinal movement of the rod 15 will be transmitted through the bell crank levers 12 and the links 10 to the eccentrics 7 moving each of these eccentrics inwardly toward the center of the shaft and thus reducing the throw of the valves and the amount of steam.

admission. The escape of fluid from the cylinder 24 will produce the reverse effect allowing the rod 15 to move outwardly, which will have the effect of increasing the 5 eccentricity of the eccentrics and hence the amount of steam admission.

The construction and operation of the 10 governor here shown which controls the admission and exhaust of oil from the cylinder 24 is fully described in the copending application of Jones and Treiber, Serial No. 842,146, filed June 1, 1914, and will be only briefly here described.

The governor consists essentially of a casting 28 divided into three chambers 29, 30 and 31. Oil is pumped into the chamber 29 through a pipe 32 which leads from the discharge of an oil pump 33 operated by a chain from the shaft 4 and the speed of 20 which, therefore, varies with the speed of the engine. From the chamber 29 the pipe 27 leads to the cylinder 24, while from the chamber 31 a discharge pipe 35 leads to the intake of the pump 33.

25 Under normal conditions the oil passes from the chamber 29 to the chamber 30 through passage 36 and from thence to the chamber 31 through the adjustable aperture 37, a small part of the oil also passing directly from chamber 29 to chamber 31 through the adjustable aperture 38. The flow through the apertures 37 and 38 under full load conditions is just equivalent to the amount of fluid discharged from the oil 35 pump 33 at the engine's maximum speed. If the speed of the engine exceeds this maximum, oil will pass from the chamber 29 through the pipe 27 to the cylinder 24 moving the rod 15 inwardly and cutting off the 40 steam admission the necessary amount.

The flow of oil through the passage 36 is, however, controlled also by the pilot valve 39 which is controlled by the pressure in the compressor receiver in the following 45 manner: From the receiver of the compressor, (not shown), a pipe 40 leads to the lower end of the cylinder 41 in which slides a piston 42 having a projecting stem 43. The stem 43 engages a lever 44 which is so balanced by means of a weight 45 and a spring 46 that it will allow the piston 42 to move upwardly at a certain predetermined pressure in the receiver. Pivoted to this 50 lever 44 is a bell crank lever 47. To one arm of the lever 47 is linked the valve 39, while to the other arm is linked a follow up lever 48, the lower end of which is fulcrumed on a pin 49 on the casing 28 and the upper end of which is secured by a yoke 50 and 55 pin 51 to the stem 22 which operates the rod 15. When the pressure in the compressor receiver reaches an amount predetermined by the balance of the lever 44 the piston 42 will move upwardly raising the lever 44 and 60 the valve 39 and shutting off the flow of oil 65

through the passage 36. The escape of the oil being thus prevented it will pass through the pipe 27 to the cylinder 24 and move the piston 23 and the rod 15 inwardly cutting down the speed of the engine. The movement of the piston 23 will, however, be transmitted back to the valve 39 to again open the passage 36 and permit the escape of the oil from the chamber 29, the parts automatically adjusting themselves so that just enough oil will be admitted to the cylinder 24 to maintain the piston 23 in such a position that the steam admission to the engine will be sufficient for the load.

Although a certain type of governor is 80 here shown and described, any form of governing mechanism furnishing a supply of fluid varying with the load on the engine could be used for operating the piston 24, and it is to be understood that while the 85 present showing and description disclose only one specified modification of the invention, other forms and modifications are included in the spirit and scope of the invention as expressed in the claims. 90

What I claim is:

1. In a steam engine governing mechanism, a shaft, valve operating eccentrics movably mounted on said shaft, a fluid operated motor operatively connected with 95 said eccentrics, and means for supplying fluid to said motor in accordance with the load on the engine.

2. In a steam engine governing mechanism, a shaft, valve operating eccentrics 100 movably mounted on said shaft, levers to move said eccentrics, an operating rod for moving said levers extending longitudinally of said shaft, a fluid operated motor for moving said rod, and means for supplying 105 fluid to said motor in accordance with the load on the engine.

3. In a steam engine governing mechanism, a shaft, valve operating eccentrics on said shaft, an eccentric controlling rod 110 extending longitudinally of said shaft, means to transmit longitudinal movement of said rod to vary the throw of said eccentrics, a fluid operated motor for moving said rod, and means for supplying fluid to said 115 motor in accordance with the load on the engine.

4. In a steam engine governing mechanism, a hollow rotatable shaft, eccentrics movably mounted on said shaft, valve rods 120 operated by said eccentrics, an eccentric operating rod extending longitudinally axially of said shaft, and having operative connections with said eccentrics to vary their throw, a fluid operated motor for moving 125 said rod, and means for supplying fluid to said motor in accordance with the load on the engine.

5. In a steam engine governing mechanism, a rotating eccentric shaft carrying 130

valve operating eccentrics sliding transversely thereon, levers pivoted in said shaft and linked to said eccentrics, a lever operating rod sliding longitudinally inside of said shaft, means to move said levers from said rod, a fluid operated motor for moving said rod and means to admit fluid to said motor in accordance with the load on the engine.

6. In a governing mechanism for steam engines, an eccentric carrying shaft having eccentric squared portions, valve operating eccentrics sliding on said squared portions, bell crank levers pivoted in said shaft each having one end linked to said eccentrics and 10 the other provided with a toothed portion, a rod sliding longitudinally of said shaft and having teeth thereon engaging said toothed portions of said bell crank levers, a stationary fluid motor for moving said 15 rod longitudinally of said shaft having a rotary connection with said rod and means to admit fluid to said motor in accordance with the load on the engine.

7. In a steam engine governing mechanism, a hollow rotatable shaft, eccentrics 25 movably mounted on said shaft, valve rods operated by said eccentrics, an eccentric operating rod extending longitudinally axially of said shaft, and having operative connections with said eccentrics to vary their 30 throw, a motor for operating said rod comprising a stationary cylinder mounted coaxially with said shaft and having a piston sliding therein, a swivel connection between said piston and said eccentric operating rod, 35 resilient means to move said piston in one direction, and means to admit fluid to said cylinder to move said piston in the other direction an amount varying with the load on the engine. 40

In testimony whereof, I have hereunto set my hand.

WARD RAYMOND.
